UNITED STATES PATENT OFFICE

FRANK N. MARIANI, OF NEW YORK, N. Y., ASSIGNOR TO BEST DIE CASTING & STAMPING CO., OF NEW YORK, N. Y., A CORPORATION OF NEW YORK

DESIGN FOR A MIRROR STAND

Application filed March 26, 1930. Serial No. 35,028. Term of patent 7 years.

To all whom it may concern:

Be it known that I, FRANK N. MARIANI, in Figure 1, the same being shown in connection with a base and mirror illustrated by dot and dash lines. I claim: The ornamental design for a mirror stand substantially as shown and described. Signed at New York, in the county of New York and State of New York, this 24th day of March, 1930.

Reference is had to the accompanying drawing forming part thereof, wherein—

FRANK N. MARIANI.
